UNITED STATES PATENT OFFICE

2,097,608

CONCENTRATION OF GOLD BEARING MATERIALS

Stanley Tucker, London, England, assignor to Minerals Separation North American Corporation, New York, N. Y., a corporation of Maryland

No Drawing. Application January 24, 1935, Serial No. 3,267. In Great Britain January 30, 1934

11 Claims. (Cl. 209—166)

The present invention relates to an improved process of extracting gold from ores and like materials by a form of physical concentration depending upon the surface properties of the material under treatment, such for example as froth flotation, and has for its general object to provide for simplicity in such extraction, as well as for high gold recovery and high gold assay of concentrate.

10 In accordance with the invention, the gold-bearing material in the state of finely-divided particles is formed into a pulp with water both in the presence of a mercurial agent and in the presence of a sulphidizing agent. By this combination of agents, as the present inventor has discovered, the gold particles present in the pulp are so modified at their surfaces that they are made amenable to subsequent concentration depending upon their surface properties.

20 Instead of the sulphidizing agent, an organic sulphur derivative of carbonic acid may be employed, the combination with such a compound of the mercurial agent having also been found by the present inventor to produce the stated effect on the surfaces of the gold particles present in the pulp. However, the claims of this application should not be construed as covering the use of organic sulphur derivatives of carbonic acid, which subject-matter is separately claimed 25 in an application Serial No. 144,314, filed May 22, 1937, which is a division of the present application.

30 In applying the process in apparatus of the kind ordinarily employed for froth flotation and in conjunction with usual frothing agents so that the concentrate floats in the form of a froth, it has been found that under suitable conditions an almost complete recovery of gold can be obtained by the process in the form of a high 35 grade concentrate.

40 The surface-modifying agents may be dispersed among the particles of the gold-bearing material during an agitation or grinding operation, carried out prior to concentration.

45 The mercurial agent may be metallic mercury or a solution of a salt thereof. Mercuric chloride may be used dissolved in an excess of sodium cyanide, a slight excess being sufficient for the purpose. This solution is believed to result in 50 the formation of a sodium mercuric cyanide, with some free sodium cyanide present.

55 Sulphidizing agents which have been found useful include sulphur, soluble sulphides or polysulphides, and sulphur dissolved in sulphides of polysulphides. As to the organic sulphur deriv-

atives of carbonic acid, they of course include alkali xanthates.

Various other agents may be present when the surface-modifying agents are acting upon the gold particles, as during the above-stated 5 preliminary agitation or grinding operation. The use in this manner of a tin salt, such as stannous chloride (SnCl_2), has been found to reduce the quantity of the mercurial agent which is required.

10 As a basis of comparison with the examples to be hereinafter given, the following test was carried out:

Comparative test

15 Low-grade gold ore obtained from the Colomines mine in the Congo was taken. This is a free gold ore containing a very small amount of pyrite and gold in a coarse condition irregularly distributed in a hard siliceous gangue. The ore was crushed until only 2% remained on a 100 mesh Tyler screen, 2% of charcoal being ground with the ore. The ore was then floated with 2 lbs. per ton of stripped blast furnace creosote, together with 0.5 lb. per ton of xanthate, producing a primary concentrate. This concentrate 20 was then cleaned by refloating with 0.5 lb. per ton of stripped blast furnace creosote and 0.2 lb. per ton of xanthate. By this means a flotation test was conducted without the employment of mercury so as to form a basis of comparison. It was only found possible to recover 62.3% of 25 the gold by this flotation procedure. The crude ore assayed 10.7 dwts. of gold per ton and the combined concentrates assayed 219 dwts. per ton, of gold. A further 34.5% of gold could be 30 removed by passing the flotation tailings twice over a corduroy strake. By increasing the grinding period from 30 minutes to a total of 60 minutes and forcing the flotation, it was found 35 possible to recover 79.1% of the gold in the flotation concentrate, but the assay of the concentrate fell to 49.7 dwts. per ton, the assay of the crude sample being in this case 8.28 dwts. of gold per ton.

40 The following is a description of certain tests which have been carried out, from which further details of the method of carrying out the invention into effect may be obtained.

Example I

45 500 grammes of the above-mentioned ore assaying 11.39 dwts. per ton and crushed at 10 mesh were taken and ground with 200 cubic centimetres of water, 0.125 lb. per ton of mercuric 55

chloride, and 0.075 lb. per ton of sodium cyanide in a pebble mill for 30 minutes, until only about 2% of the material remained on a screen of 80 meshes to the lineal inch.

5 When the grinding had proceeded for 20 minutes, the following agents were added to the mill:

	Pounds per ton
Sodium polysulphide	2
Anglo Persian fuel oil	0.45
Blast furnace creosote	0.078
Pine oil	0.08

The sodium polysulphide was prepared by heating a solution of commercial sodium sulphide with 5% by weight of flowers of sulphur on the weight of sodium sulphide present.

15 Flotation was carried out in a sub-aeration flotation machine using a first addition of 0.25 lb. per ton of xanthate, agitation with the 20 xanthate for one minute, and removal of froth for three minutes. Thereupon a second addition of 0.25 lb. per ton of xanthate was made, agitation continued for one minute, and a second froth taken for three minutes. The combined 25 concentrates assayed 181.8 dwts. per ton and showed a recovery of 98.8% of the gold.

Example II

In another test using the same agents and 30 procedures as those last described, except that sodium sulphide was employed instead of polysulphide, and the grinding was continued for 40 minutes, until the ore would pass a screen having 100 meshes to the lineal inch, a recovery 35 of 97.9% of the gold was obtained in a concentrate assaying 242.4 dwts. of gold.

In each of the two examples above given, it 40 was found that gold particles of quite considerable size, such as would correspond to a mesh 45 of about 80 or 100 to the lineal inch, were floated. Such gold particles cannot be normally floated by standard procedures, such as first described in the comparative test.

Similar results were obtained when cyanide 45 alone was added to the mill and mercuric chloride added to the pulp after grinding and before admission to the flotation machine, but it was found in this case better to employ a somewhat larger quantity of sodium cyanide, up to 0.45 50 lb. per ton.

Example III

In this example the same ore was employed as before, but 0.8 of a lb. of mercury per ton of 55 ore was added in the metallic state to the grinding mill in place of the addition of mercuric chloride and sodium cyanide. The ore was ground to 80 mesh, was sulphidized with sodium sulphide as before, and floated by the aid of the 60 following agents:

	Pound per ton
Anglo Persian fuel oil	0.45
Blast furnace creosote	0.078
Pine oil	0.08
Xanthate	0.5

The first three reagents were added in the grinding mill, and the xanthate to two equal portions to the flotation machine. The sodium sulphide in the amount of 2 lbs. per ton was added to the grinding mill along with the flotation oils.

The crude ore assayed 16.19 dwts. of gold per ton, the concentrates 204.4 dwts. per ton, and the tailings 0.1 dwt. per ton, giving a recovery 70 of 99.4% of gold in the concentrate.

Example IV

In this example the ore and general conditions were the same as in Example III, but the mercury, oils and sulphidizing agent were all added to the mill at the beginning of the grinding stage. The crude ore assayed 11.16 dwts. per ton, sodium polysulphide (12.5% flowers of sulphur) was the sulphidizing agent employed, the quantity of this agent was 1.0 lb. per ton, and the ore was ground to pass a 100 mesh screen, the other conditions being the same as in Example III. The recovery of gold was 98.5% and the concentrate assayed 343.6 dwts. per ton.

Broadly similar results with a somewhat lower grade of concentrates have been obtained on Rand Banket ores, and even in the case of an ore assaying only 1.84 dwts. per ton, a recovery of 97.7% of the gold has been obtained with the concentrate containing 37.4 dwts. per ton of gold. All of the concentrates mentioned could, by retreatment in bulk, be reconcentrated to a much higher grade.

Example V

500 grammes of ore obtained from Klerksdorp, South Africa, were taken for the purpose of this example. This ore is partly oxidized gold ore containing iron sulphide, and assayed 17.45 dwts. per short ton of 2000 lbs. It was ground to pass a screen having ten meshes to the lineal inch and made into a pulp with 250 cubic centimetres of water, mercury in the metallic state being added at the rate of 1.6 lbs. per ton. The pulp was ground in a pebble mill for forty minutes and, after thirty minutes of this grinding, there were added to the mill 2 lbs. per ton of sodium polysulphide, 0.45 lb. per ton of Anglo Persian fuel oil, 0.08 lb. per ton of pine oil, 0.078 lb. per ton of blast furnace creosote, and 0.38 lb. per ton of oleic acid. These additional agents, including the oleic acid, were therefore ground with the ore for ten minutes.

The resulting material was about such as would pass a screen having 100 meshes to the lineal inch. It was subjected to froth flotation with two additions of 0.25 lb. per ton of potassium xanthate, and as a result 96% of the gold in the ore was obtained in a concentrate which assayed 190.4 dwts. per ton of gold. Omission of the oleic acid during the grinding operation showed a reduced recovery compared with the above results.

Example VI

In another test the same ore from Klerksdorp was taken and the same conditions observed, but the sodium polysulphide and oleic acid were omitted, and in their place 2 lbs. per ton of potassium xanthate was added in the grinding mill, the other reagents remaining as before. In this case the sample of ore assayed 12.29 dwts. per ton, and a recovery of 97.7% of the gold was made in a concentrate assaying 177.2 dwts. per ton.

It will be observed that the addition of the xanthate along with the mercury so that the particles become modified by the xanthate during the action of the mercury upon them is the distinguishing feature of this example, the subsequent use of xanthate merely in the flotation operation not being equivalent.

Example VII

This is an example of the employment of sulphur as the sulphidizing agent. In this case 500 grammes of crude ore containing 8.68 dwts.

of gold per ton were concentrated by the employment of 0.8 lb. per ton of mercury, which was ground along with the ore and 0.8 lb. per ton of flowers of sulphur until the ore would pass a screen having 100 meshes to the lineal inch. 19 grammes of a concentrate which assayed 223.4 dwts. of gold per ton were recovered, showing a recovery of 97.8% of the gold present. The other agents employed were:

	Pound per ton
Anglo Persian fuel oil	0.45
Blast furnace creosote	0.078
Pine oil	0.08
Xanthate	0.8

In another case where the ore contained 17.52 dwts. per ton of gold, under conditions parallel to the preceding example the recovery was 99.2% of the gold and the concentrate assayed 434.4 dwts. of gold per ton. In this instance the ore was only ground to pass a screen having 80 meshes to the lineal inch, and the mercury, oils, and sulphidizing agent were all added to the mill at the beginning of the grinding stage, while in the preceding example the mercury was added alone in the first instance and the other reagents only after 20 minutes grinding.

Example VIII

This example is intended to show the effect of using a proportion of stannous chloride along with mercuric chloride with the object of reducing the quantity of mercury required. 500 grammes of ore were ground in 250 cubic centimetres of water for 30 minutes in the presence of 0.05 lb. per ton of Anglo Persian fuel oil, 0.08 lb. per ton of pine oil, 0.078 lb. per ton of blast furnace creosote, and 3.5 cubic centimetres of a 5% solution of $HgCl_2$ to which had been added 0.3 cubic centimetre of a 50% solution of $SnCl_2$, the latter mixture being gently warmed prior to its addition to the pulp so as to precipitate the mercury. After 30 minutes grinding 2 lbs. per ton of polysulphide were added, and grinding was continued for 10 minutes, until the ore passed a screen having 120 meshes to the lineal inch.

The pulp was then floated with the aid of 0.75 lb. per ton of potassium xanthate. The crude ore assayed 22 dwts. per ton of gold, the concentrate assayed 244 dwts. per ton, and a recovery of 98.2% of the gold was effected.

Example IX

The following example shows the effect of working up the mercury into an emulsion with fuel oil prior to its addition to the pulp. 0.8 lb. per ton of mercury was worked up with 0.45 lb. per ton of Anglo Persian fuel oil and added to a pulp containing 500 grammes of 10 mesh ore. The whole was ground with blast furnace creosote and pipe oil in the same proportions as in the preceding example and with 2 lbs. per ton of polysulphide until the ore would, in the main, pass a screen having 150 meshes to the lineal inch. Flotation with xanthate as before showed a recovery of 98.4% of gold in a concentrate assaying 137.8 dwts. per ton, the crude ore assaying 27 dwts. per ton.

Example X

The following example is of an instance in which concentration was effected not by froth flotation, but by a film float method, and shows that a useful recovery can be obtained when the ore is treated with mercury and subsequently separated by this method.

500 grammes of a gold ore, crushed to pass a screen having 10 meshes to the lineal inch, were ground with 225 cubic centimetres of water to pass a screen having 80 meshes to the lineal inch, the following agents being added to the mill:

	Pounds per ton
Mercury	0.8
Flowers of sulphur	0.8
Anglo Persian fuel oil	5.5 10

After grinding the pulp was carefully deslimed, and the deslimed portion was passed three times over the spitzkast. The gold particles were removed as a film at the overflow, while the residue was caught at the spigot of the spitzkast. The results on the material fed to the spitzkast were as follows:

	Wt. gms.	Au dwts. per short ton	Distribu- tion percent Au
Feed	323	9.57	100
Film float	14	220.8	75.8
Spigot product	309	3.2	24.2 25

I claim:

1. A process for the concentration of a gold-bearing material consisting in forming a pulp of finely-divided particles of the gold-bearing material with water in the presence of a mercurial agent and a sulphidizing agent, so that the surfaces of the gold particles in the pulp are modified by said agents and said gold particles made amenable to concentration depending upon their surface properties, and concentrating said gold particles from the material by flotation.

2. A process for the concentration of a gold-bearing material consisting in forming a pulp of finely-divided particles of the gold-bearing material with water in the presence of a mercurial agent and a sulphidizing agent, so that the surfaces of the gold particles in the pulp are modified by said agents and said gold particles made amenable to concentration depending upon their surface properties, and concentrating said gold particles from the material by froth flotation.

3. A process for the concentration of a gold-bearing material consisting in the preliminary step of agitating a pulp with water of finely-divided particles of the gold-bearing material in the presence of a mercurial agent and a sulphidizing agent, so that the surfaces of the gold particles in the pulp are modified by said agents and said gold particles made amenable to concentration depending upon their surface properties, and the subsequent step of concentrating said gold particles from the material by flotation.

4. A process for the concentration of a gold-bearing material consisting in the preliminary step of grinding the gold-bearing material with water into a pulp of finely-divided particles in the presence of a mercurial agent and a sulphidizing agent, so that the surfaces of the gold particles in the pulp are modified by said agents and said gold particles made amenable to concentration depending upon their surface properties, and the subsequent step of concentrating said gold particles from the material by flotation.

5. A process for the concentration of a gold-bearing material consisting in forming a pulp of finely-divided particles of the gold-bearing

- material with water in the presence of metallic mercury and a sulphidizing agent, so that the surfaces of the gold particles in the pulp are modified by said mercury and sulphidizing agent 5 and said gold particles made amenable to concentration depending upon their surface properties, and concentrating said gold particles from the material by flotation.
6. A process for the concentration of a gold-bearing material consisting in forming a pulp of finely-divided particles of the gold-bearing material with water in the presence of mercuric chloride and a sulphidizing agent, so that the surfaces of the gold particles in the pulp are modified by said mercuric chloride and sulphidizing agent and said gold particles made amenable to concentration depending upon their surface properties, and concentrating said gold particles from the material by flotation.
- 10 7. A process for the concentration of a gold-bearing material consisting in forming a pulp of finely-divided particles of the gold-bearing material with water in the presence of a mercurial agent and a sulphidizing agent, so that the surfaces of the gold particles in the pulp are modified by said agents and said gold particles made amenable to concentration depending upon their surface properties, said mercurial agent comprising mercuric chloride dissolved in an excess of 15 sodium cyanide, and concentrating said gold particles from the material by flotation.
- 20 8. A process for the concentration of a gold-bearing material consisting in forming a pulp of finely-divided particles of the gold-bearing material with water in the presence of a mercurial agent and sulphur, so that the surfaces of the gold particles in the pulp are modified by said mercurial agent and sulphur and said gold particles made 25

- material with water in the presence of metallic mercury and a sulphidizing agent, so that the surfaces of the gold particles in the pulp are modified by said mercury and sulphidizing agent 5 and said gold particles made amenable to concentration depending upon their surface properties, and concentrating said gold particles from the material by flotation.
6. A process for the concentration of a gold-bearing material consisting in forming a pulp of finely-divided particles of the gold-bearing material with water in the presence of mercuric chloride and a sulphidizing agent, so that the surfaces of the gold particles in the pulp are modified by said mercuric chloride and sulphidizing agent and said gold particles made amenable to concentration depending upon their surface properties, and concentrating said gold particles from the material by flotation.
- 10 7. A process for the concentration of a gold-bearing material consisting in forming a pulp of finely-divided particles of the gold-bearing material with water in the presence of a mercurial agent and a sulphidizing agent, so that the surfaces of the gold particles in the pulp are modified by said agents and said gold particles made amenable to concentration depending upon their surface properties, said mercurial agent comprising mercuric chloride dissolved in an excess of 15 sodium cyanide, and concentrating said gold particles from the material by flotation.
- 20 8. A process for the concentration of a gold-bearing material consisting in forming a pulp of finely-divided particles of the gold-bearing material with water in the presence of a mercurial agent and sulphur, so that the surfaces of the gold particles in the pulp are modified by said mercurial agent and sulphur and said gold particles made 25

CERTIFICATE OF CORRECTION.

Patent No. 2,097,608.

November 2, 1937.

STANLEY TUCKER.

It is hereby certified that error appears in the printed specification of the above numbered patent requiring correction as follows: Page 1, first column, line 54, for the word "of" read or; same page, second column, lines 52-53, for "asseying" read assaying; page 2, first column, line 68, for the word "to" read in; and that the said Letters Patent should be read with these corrections therein that the same may conform to the record of the case in the Patent Office.

Signed and sealed this 1st day of February, A. D. 1938.

Henry Van Arsdale,
(Seal) Acting Commissioner of Patents.
